UNITED STATES PATENT OFFICE.

JAMES W. SHAW, OF CHICAGO, ILLINOIS.

CONTINUOUS WASHING MACHINE.

Renewal of application Serial No. 101,221, filed April 10, 1926. This application filed December 12, 1927.
Serial No. 239,618.

This invention relates to that type of washing machines in which the material or stock operated on has continuous travel between the inlet and outlet ends of the machine, and 5 has for its various objects:

To provide a structural formation and combination of alternating, longitudinal, fixed and movable rails or bars, and superimposed and yielding pressure and suction heads 10 or heads, adapted to attain a thorough and rapid cleansing operation on the stock or material in its travel through the mechanism.

To provide means and mechanisms whereby the joint operation of the pressure and suction heads, and the rails above referred to, may be readily adjusted for effective operation on different grades, quantities, etc., of the stock or material to be cleansed, all as will hereinafter more fully appear.

20 In the accompanying drawings:

Fig. 1, is a longitudinal section of a washing machine illustrating the preferred arrangement of parts of the invention.

Fig. 2, is a top view of the same.

25 Fig. 3, is a sectional top view, on line 3—3,

Fig. 5.

Fig. 4, is a transverse section on line 4—4,

Fig. 1.

Fig. 5, is a similar view on line 5—5, Fig. 1.

30 Like reference numerals indicate like parts in the different views.

The main body or tank 1 of the machine is of the usual open top box form shown, at the outlet end of which is arranged the usual 35 pair of press or wringer rolls 2, the meeting perimeters of which are on a plane near the top of the tank 1 as shown.

In the present improvement, a series of longitudinally extending rails or bars 3 are 40 fixedly secured, in transverse spaced relation to each other, within the tank 1 and about the midheight of the same by transverse bracket supports 4 in the interior of the tank. Near the outlet end of the tank and adjacent 45 to the press rolls 2, the rails 3 are provided with upwardly inclined end portions 3' adapted to aid in directing the stock or material operated on, to and between said press rolls, and with a view to a more effective feeding action of the mechanism, the top face of 50 each end portion 3' of the rails 3 is of a toothed or corrugated formation as illustrated in Fig. 1.

A companion series of movable rails or bars 55 5 are arranged intermediate of the fixed rails

3 aforesaid, and are supported by the crank rods 6 of a pair of crank members 7 journaled in longitudinally spaced relation in the side walls of the tank 1, and from which the rails 5 will receive movement corresponding with the circular throw of the crank rods 6, and will receive a rising and forward movement combined with a downward and rearward movement with relation to the companion series of fixed rails 3. The 60 movable rails or bars 5, are also provided with upwardly inclined portions 5' corresponding with the inclined portions 3' of the fixed rails 3 and adapted to coact therewith to move the stock or material undergoing treatment to and between the press rolls 2 aforesaid. In the preferred formation, the top edges of the rails 5 are formed with teeth or corrugations 8 along their entire length, with a view to attain a more effective feed of the stock through the tank and from the same to the press rolls 2 in a continuous operation of the machine. In addition said movable rails 5 are formed with a 70 series of vertical orifices or passages 9, adapted to permit a free downward flow of the washing fluid in the compressing action of the mechanism.

In the construction shown the crank members 7 aforesaid are connected together so 85 as to operate in unison by a driving counter-shaft 10 journaled on the tank casing and having bevel gear connections 11 with said crank members and the usual pulley 12 or like connection with the power source.

A material part of the present improvement involves a combination with the above described longitudinally arranged fixed and movable rails 3 and 5 of a superimposed pressure and suction means whereby an effective 95 down and up movement of the washing fluid through the stock or material is attained in the progress of the same through the machine.

The pressure and suction means above referred to, preferably comprises a plurality of transversely extending heads 13, in longitudinal spaced relation to each other, and depending from an overhead supporting frame 14, to which they are connected in a 100 vertically and in a longitudinally yielding manner, preferably by a construction of parts as follows.

Each pressure and suction head 13 is slid- 105 ily mounted on one or more guide rods 15 110

depending from longitudinal rails 16 of the overhead frame 14 aforesaid, said rails being in turn slidingly mounted on transverse end rails 17 of the frame 14.

5 The vertical yielding movement of each head 13 is effected on the rods 15 against the tendency of springs 18, preferably encircling said rods, to maintain the head 13 in its down position and at rest upon a stop collar on the 10 lower end of each rod 15. The longitudinal yielding movement of each head 13 is attained by a sliding movement upon the longitudinal rails 16, aforesaid, against the tendency of springs 18 bearing against opposite 15 sides of said head with a tendency to return and yieldingly maintain the head in a normal position midway of said springs.

In the construction shown, adjustable stop collars 20 on the longitudinal rails 16, provide 20 adjustable abutments for the adjacent ends of a pair of springs 19, and afford means for regulating the tension of the same.

With a view to a vertical adjustment of the pressure of suction heads 13 with relation to 25 the fixed and movable rails 3 and 5 aforesaid, to compensate for varieties of the quantity or nature of the stock undergoing treatment, the overhead frame 14 is carried by vertical corner posts 21 adapted for manual turning 30 movement and provided with screw threaded upper ends having engagement in correspondingly formed sockets on the frame 14, as shown.

The pressure and suction heads 13 of the 35 present construction are of an open bottom conical form, the closed apex of each of which is slidingly mounted on its guide rod 15, as above described. In the preferred construction shown, an auxiliary cone shaped head 13' 40 of a smaller size than the main head 13, is fixed inside the head 13, with the bottom margin of the head 13' a short distance above that of the head 13, as shown.

The operation of the apparatus is as follows:

The stock to be washed, either textile fabric, raw wool, etc., is fed in any suitable manner into the receiving end of the tank 1, and upon the receiving ends of the longitudinal 50 fixed and movable rails 3 and 5. With the mechanism in operation, the movable rails 5 act to gradually move the stock along the tank 1 and beneath the pressure and suction heads 13 and in the gradual passage of the 55 stock beneath said heads, the same is repeatedly pressed up against the open bottom of the heads 13, causing the air confined in said heads to impart a downward movement of the washing fluid through said stock as the 60 same is moved upward by the movable rails 5. With a succeeding downward movement of the stock an upward movement of the 65 washing fluid through the same is effected by the suction produced in the heads 13, by such downward movement of the stock.

Repeated actions of said heads as above set forth, in the passage of the stock from one end to the other of the machine is adapted to attain a very effective washing of the stock, as the same reaches the upwardly inclined 70 portions 3' and 5' of the fixed and movable rails 3 and 5, to be delivered automatically and gradually to press rolls 2 for a final expression of the washing fluid from the stock.

Having thus fully described my invention, 75 what I claim as new, is:—

1. In a washing machine, the combination of a tank, a series of longitudinal rails fixed in said tank, a series of longitudinal rails movably mounted in said tank intermediate 80 said fixed rails, means for imparting a combined upward, forward, downward and rearward movement to said movable rails, and an open bottom pressure and suction head mounted in adjacent and superimposed relation to said rails.

2. In a washing machine, the combination of a tank, a series of longitudinal rails fixed in said tank, a series of longitudinal rails movably mounted in said tank intermediate 90 said fixed rails, means for imparting a combined upward, forward, downward and rearward movement to said movable rails, and an open bottom pressure and suction head resiliently mounted in adjacent and superimposed relation to said rails.

3. In a washing machine, the combination of a tank, a series of longitudinal rails fixed in said tank, a series of longitudinal rails movably mounted in said tank intermediate 100 said fixed rails, means for imparting a combined upward, forward, downward and rearward movement to said movable rails, and an open bottom pressure and suction head resiliently mounted for vertical and longitudinal movement above said rails.

4. In a washing machine, the combination of a tank, a series of longitudinal rails fixed in said tank, a series of longitudinal rails movably mounted in said tank intermediate 110 said fixed rails and formed with a plurality of vertical passages along their length, means for imparting a combined upward, forward, downward and backward movement to said movable rails, and an open bottom pressure and suction head mounted in adjacent and superimposed relation to said rails.

5. In a washing machine, the combination of a tank, a series of longitudinal rails fixed in said tank, a series of longitudinal rails movably mounted in said tank intermediate 120 said fixed rails, the fixed and movable rails having upwardly inclined portions at the discharge end of the machine, means for imparting a combined upward, forward, downward and rearward movement to said movable rails, and an open bottom pressure and suction head mounted in adjacent and superimposed relation to said rails.

6. In a washing machine, the combination 130

- of a tank, a series of longitudinal rails fixed in said tank, a series of longitudinal rails movably mounted in said tank intermediate said fixed rails and having a corrugated 5 upper edge, means for imparting a combined upward, forward, downward and rearward movement to said movable rails, and an open bottom pressure and suction head mounted in adjacent and superimposed relation to said 10 rails.
7. In a washing machine, the combination of a tank, a series of longitudinal rails fixed in said tank, a series of longitudinal rails movably mounted in said tank, intermediate 15 said fixed rails, means for imparting a combined upward, forward, downward and rearward movement to said movable rails, the same comprising a pair of crank members the crank rods of which carry the movable 20 rails, and an open bottom pressure and suction head mounted in adjacent and superimposed relation to said rails.
8. In a washing machine, the combination of a tank, a series of longitudinal rails fixed 25 in said tank, a series of longitudinal rails movably mounted in said tank intermediate said fixed rails, means for imparting a combined upward, forward, downward and rearward movement to said movable rails, an 30 overhead frame, a depending guide rod on said frame, an open bottom pressure and suction head slidingly mounted on said guide rod, and a spring associated with said rod and head for effecting a downward movement of 35 said head.
9. In a washing machine, the combination of a tank, a series of longitudinal rails fixed in said tank, a series of longitudinal rails movably mounted in said tank intermediate 40 said fixed rails, means for imparting a combined upward, forward, downward and rearward movement to said movable rails, an overhead frame having longitudinal guide rails, a depending guide rod sliding on said 45 rails, springs at opposite sides of said guide
- rod for maintaining a central position of the same, an open bottom pressure and suction head slidingly mounted on said guide rod, and a spring associated with said rod and head for effecting a downward movement of 50 the head.
10. In a washing machine, the combination of a tank, a series of longitudinal rails fixed in said tank, a series of longitudinal rails movably mounted in said tank intermediate 55 said fixed rails, means for imparting a combined upward, forward, downward and rearward movement to said movable rails, a vertical adjustable overhead frame, and an open bottom pressure and suction head carried by 60 said frame in adjacent relation to the fixed and movable rails aforesaid.
11. In a washing machine, the combination of a tank, a series of longitudinal rails fixed in said tank, a series of longitudinal rails 65 movably mounted in said tank intermediate said fixed rails, means for imparting a combined upward, forward, downward and rearward movement to said movable rails, an overhead frame, vertical posts connected to 70 said frame by adjusting screw thread formations, and an open bottom pressure and suction head carried by said frame in adjacent relation to the fixed movable rails aforesaid.
12. In a washing machine, the combination 75 of a tank, a series of longitudinal rails fixed in said tank, a series of longitudinal rails movably mounted in said tank intermediate said fixed rails, means for imparting a combined upward, forward, downward and rearward movement to said movable rails, an overhead frame, vertical posts connected to 80 said frame by adjusting screw thread formations, and an open bottom pressure and suction head resiliently mounted on said frame 85 in adjacent relation to the fixed and movable rails aforesaid.

In testimony whereof I hereunto affix my signature.

JAMES W. SHAW.
